UNITED STATES PATENT OFFICE.

HORACE H. EWAN, OF BALTIMORE, MARYLAND.

GAS-HEATER FOR WATER-BACKS.

1,314,860.

Specification of Letters Patent. Patented Sept. 2, 1919.

Application filed March 20, 1917, Serial No. 156,109. Renewed July 11, 1919. Serial No. 310,207.

To all whom it may concern:

Be it known that I, HORACE H. EWAN, a citizen of the United States, residing at Baltimore, in the State of Maryland, have invented certain new and useful Improvements in Gas-Heaters for Water-Backs, of which the following is a specification.

This invention relates to portable or detachable gas heaters for the waterbacks of cooking stoves and ranges, and its object is to provide a simple and efficient device of this character which may be used for cooking as well as for water heating.

In order that the invention may be readily understood, reference is had to the accompanying drawings, forming a part of this specification, and in which,

Figure 1 is a partial front elevation of an ordinary stove or range, showing how the gas is supplied to my improved burner;

Fig. 2 is a vertical section through the firebox of such a stove, showing the waterback, and my improved burner in operative position with respect thereto;

Fig. 3 is a rear sectional elevation of my improved burner on an enlarged scale; and,

Fig. 4 is a detail showing one of the spacing screws which I employ.

Referring to the drawings in detail, 1 designates the usual waterback which is located in the firebox of the stove, and connected with a suitable tank or boiler (not shown) by means of the usual pipes 2. 3 designates the grate, and 4 the ashpit door, both of which are of the usual or any desired construction. 5 indicates the oven and 6 the plate or cooking surface of the stove. At 6^a is illustrated the usual smoke flue.

My improved burner consists of a box or casing 7, preferably made of cast iron, and rectangular in form, as clearly shown in the drawing. The burner is relatively long and narrow and rests upon the grate 3 with one of its longitudinal side faces in close proximity to the inside wall of the waterback 1. In the side face of the burner adjacent the waterback are formed a plurality of relatively small holes 8, such holes being preferably disposed in horizontal rows and arranged in staggered relation, as shown in Fig. 3. A plurality of spacing screws 9 are set into the front wall of the burner and abut against the adjacent wall of the waterback, thus properly spacing the burner from the waterback. The distance between the

burner and waterback may be adjusted, as desired, by screwing these screws in or out.

The gas is supplied to the burner through a pipe 10, which taps the burner adjacent one end at the rear where there is preferably formed a boss 7^a, to receive the pipe. A suitable air and gas mixing device is provided and may be of any desired construction. As shown, in Fig. 3, it consists of a cap 11, screw-threaded on to the end of pipe 10 and provided with a number of holes 12. A relatively small nipple 13 is screwed into the center of the cap 11 and is connected by means of a coupling 14 with a pipe 15, to the end of which a hose 16 is attached. This hose 16 is led out through a draft opening in the ashpit door 4, as shown in Fig. 1, or through some other door, so as to avoid making any special opening in the stove casting to accommodate it. This is facilitated by bringing the pipe 15 down through the grate, as shown in Fig. 2, into the ashpit.

Gas entering the pipe 15 discharges in the form of a jet through the nipple 13, and, drawing air in through the holes 12, the mixture of gas and air passing through the pipe into the interior of the burner, whence it issues through the jet openings 8. When the flame is ignited, these jets impinge against the surface of the waterback 1 and produce an intense heat. The length of the jets may be regulated by means of the screws 9, as described, in accordance with the gas pressure being used.

It will be observed that the jets issuing from the face of the burner and impinging upon the waterback form practically a continuous sheet of flame, and that no air, other than that already mixed with the gas, is admitted to the space between the burner and waterback, except at the edges. The flame and heated products of combustion pass upwardly along the waterback and impinge against the plate 6, whence they pass rearwardly into the flue 6^a.

Although the heat thus generated is sufficient in many instances for cooking on the plate 6, I prefer to provide means for producing an additional supply of heat under this plate, as shown in the drawings. This means consists of a pair of tubes 18, set in bosses 17, formed on the top of the burner and communicating with the interior thereof. It will be evident that these tubes are slightly inclined rearwardly, as shown,

so as to direct the flame to the proper point. At the top of each tube 18 is mounted a cap 19, rotatable on the tube and provided with a handle 20, by means of which it may be 5 conveniently turned. The end of the tube is provided with radial openings 22, and the cap has similar openings 21, the arrangement being such that the openings 21—22 may be brought into and out of registry by 10 turning the cap, as will be evident. From the above it will be seen that the mixture of gas and air from the interior of the burner 7 passes upwardly through the tubes 18 and issues from the openings 21 in the 15 form of jets. When ignited, these jets produce a powerful heat under the cooking surface 6 of the stove.

It will be noted that my improved burner can be mounted in the firebox of any ordinary cook stove without change, and can 20 be easily removed when occasion requires.

What I claim is:

1. A gas heater for the waterbacks of stoves and the like comprising a rectangular 25 burner box having a continuous unbroken face adapted to be disposed adjacent to and parallel with a wall of the waterback, said face being provided with jet openings,

means carried by such face for spacing the same from the waterback, and means for 30 supplying a mixture of gas and air to the interior of said burner box.

2. A gas heater for the waterbacks of stoves and the like comprising a rectangular 35 burner box having a continuous unbroken face adapted to be disposed adjacent to and parallel with a wall of the waterback, said face being provided with jet openings, adjustable spacing screws set into such face for regulating the distance between the 40 same and the waterback, and means for supplying a mixture of air and gas to the interior of said burner box.

3. In a gas heater for the waterbacks of stoves and the like, a burner comprising a 45 box having one face adapted to be disposed adjacent the waterback and provided with jet openings, means for supplying gas to said box, a pipe projecting up from said box, and having lateral jet openings at its 50 top, and a rotatable cap for controlling the flow of gas from said last named jet openings.

In testimony whereof I have affixed my signature.

HORACE H. EWAN.
